US0D1017815S

(12) **United States Design Patent** (10) **Patent No.:** **US D1,017,815 S**
(45) **Date of Patent:** **** Mar. 12, 2024**

(54) **WAX MELTING MACHINE**

(71) Applicant: **Huang Yu**, Guangdong (CN)

(72) Inventor: **Huang Yu**, Guangdong (CN)

(**) Term: **15 Years**

(21) Appl. No.: **29/899,146**

(22) Filed: **Aug. 4, 2023**

(51) **LOC (14) Cl.** **24-01**

(52) **U.S. Cl.**

USPC **D24/200**

(58) **Field of Classification Search**

(57) **CLAIM**

The ornamental design for a wax melting machine, as shown and described.

DESCRIPTION

FIG. 1 is a front, right and top perspective view of a wax melting machine, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The broken lines depict portions of the wax melting machine that form no part of the claimed design. The dot-dash broken lines in FIGS. 1 and 9 depict the boundaries of the enlargements that form no part of the claimed design.

1 Claim, 9 Drawing Sheets
